DESIGN FOR A WALL PLATE

Gunnar B. Nystrom, Cleveland Heights, Ohio, assignor to The Republic Brass Company, Cleveland, Ohio, a corporation of Ohio

Application February 25, 1942, Serial No. 105,975

Term of patent 14 years

To all whom it may concern:

Be it known that I, Gunnar B. Nystrom, a citizen of the United States, residing at Cleveland Heights, in the county of Cuyahoga and State of Ohio, have invented a new, original, and ornamental Design for a Wall Plate, for use with plumbing, of which the following is a specification, reference being had to the accompanying drawing, forming a part thereof, in which,

Fig. 1 is a front plan view of a wall plate embodying my design;

Fig. 2 is a rear plan view of the wall plate; and

Fig. 3 is an edge view of the wall plate showing the same partly in section.

I claim:

The ornamental design for a wall plate, substantially as shown.

GUNNAR B. NYSTROM.
